EXOTHERMIC DEVICE

Ferdinand Racen, Webster Groves, Mo., assignor
to W. G. Shelton Company, St. Louis, Mo., a
corporation of Missouri

Application September 30, 1935, Serial No. 42,721

7 Claims. (Cl. 132—36.2)

The invention relates to exothermic pads such as are used particularly in the waving of human hair, and the invention consists in a novel container for the exothermic material and in the means and method of applying moisture or other agent to the exothermic material to start the chemical reaction thereof.

It has been the general practice in using such pads to tightly seal the exothermic material in a closed envelope which the operator would perforate at the time of applying the pad to the tress of hair so that moisture from a saturated element applied to the exothermic pad would combine with the exothermic material to start the chemical reaction. In some instances, the envelope would be perforated at the time of manufacture of the pad and the perforations temporarily closed, more or less effectively, by a member to be removed by the operator at the time of applying the pad to the tress of hair.

With either of these constructions, or other similar adaptations of the exothermic pad, there is an undesirable sifting out or leakage of the exothermic material from the interior of its envelope which is not only unsightly but is otherwise objectionable because the exothermic material contacting with moisture on the skin, lips, or eyes of the operator and the customer, may cause discomfort or even inflict substantial injuries.

The main object of the present invention is to retain the entire quantity of exothermic material within the pad at all times, during its use as well as up to the period of use, and thereby avoid the leakage referred to above.

Another object of the invention is to transmit moisture or other starting agent to the exothermic material over a substantial area of the latter as distinguished from restricted points only.

These and other detail objects of the invention will be apparent from the following detailed description and by reference to the accompanying drawing, in which—

Figure 1 is a view of an exothermic pad embodying the invention and showing the member containing the reaction starting agent applied to the pad.

Figure 2 is a transverse section taken substantially on the line 2—2 of Figure 1 but is drawn on an enlarged scale to more clearly illustrate the structure.

The pad consists essentially in a back member 1 and a front member 2 forming the walls of

a closed envelope for the exothermic material or substance 3 which may include calcium oxide or other ingredients commonly used for similar purposes.

Preferably, back member 1 will be of aluminum foil or other flexible, impervious material. Front member 2 is preferably formed of paper, cloth, or similar material characterized by the quality of being able to transmit moisture quickly by capillary attraction throughout its width and length 10 and particularly from face to face.

The portions of members 1 and 2 adjacent all four edges of the pad are cemented together and folded over as illustrated at 4 to form a tight seal.

In applying the pad to a tress of hair, a sheet 5 of flannel, or similar absorbent material, is dipped in water or other suitable reaction starting liquid and is laid over the inner face of member 2 of the pad. The pad and treated sheet 20 5 are immediately applied to the tress of hair, being wrapped closely around the same and secured in place by a clamp such as is in general use. Member 2 operates automatically to transmit moisture from sheet 5 to its inner face and 25 to the adjacent particles of the exothermic material. The resulting exothermic reaction generates sufficient heat to set the hair in the usual manner.

No part of the pad is perforated at any time 30 and it is unnecessary for those handling the completed pads to take precautions against the presence of the exothermic material where it is not wanted during the packing, shipping, or use 35 of the pad.

It has been found that a paper formed of pineapple husk fibre and approximately .004 of an inch in thickness constitutes an excellent material for the inner member 2 of the pad, but it will be understood that sheets of thin blotting 40 paper or other papers or fabrics of silk, linen, cotton, or other material, having the liquid transmissive characteristic referred to, may be used for the inner member of the pad. The complete envelope for the exothermic mix may be formed 45 of the liquid transmitting material and may have a backing of foil or the like applied to one face without being folded over and cemented at the edges as shown.

Heavier paper, parchment, or other foils may 50 be substituted for the aluminum foil indicated as preferred in the formation of back member 1 of the pad. Reaction starting liquid may be applied to the inner face 2 of the pad by directly 55

moistening the same with a brush or otherwise instead of relying upon its being moistened from the usual flannel wrapping. Substituting different materials as suggested and varying the means of applying moisture to the pad and other modifications of the invention may be made without departing from the scope of the invention as expressed in the claims and the exclusive use of all such modifications is contemplated.

10 I claim:

1. As a complete unit of manufacture and application, a container, and exothermic substance therein, at least a portion of said container in contact with said substance being of imperforate material which readily transmits a liquid therethrough and another portion of said container in contact with said substance being of material which is highly resistant to the passage of moisture therethrough.

15 2. An imperforate envelope for containing exothermic material and applicable therewith as an individual unit to a tress of hair, one wall of said envelope being of material characterized by a high degree of capillarity, the remainder of said envelope being of metal foil.

20 3. A hair waving pad consisting of an imperforate envelope, exothermic material therein, one wall of said envelope being of material having a high degree of capillary attraction for moisture and the remainder of said envelope being of form-sustaining material relatively impervious to moisture, said elements constituting a unit applicable to a tress of hair independently of other pad structure for retaining exothermic material and 25 for distributing moisture thereto.

30 4. As a complete article of manufacture, a hair waving pad consisting solely of a flat envelope

35 having one wall of material having a high degree of capillary attraction for moisture, and having another wall of material substantially impervious to moisture, the adjacent edge portions of said walls being cemented together and folded over to 5 form a closed envelope, and an exothermic substance contained in said envelope.

6. A container for powdered exothermic chemicals, said container comprising an envelope with one of its side walls consisting of a single thickness of imperforate material of insufficient thickness to possess substantial absorbent value but having a high degree of capillary attraction for moisture and with the other of its side walls consisting of a single thickness of imperforate material which is substantially impervious to moisture.

10 7. A container for powdered exothermic chemicals, said container comprising an envelope with one of its side walls consisting of a single thickness of paper made from pineapple husks and with the other of its side walls consisting of a single thickness of flexible metal foil of sufficient thickness and stiffness to hold the envelope and its contents in curved position enclosing a tress 15 of hair for a waving operation.

20 8. As a complete article of manufacture, a hair waving pad consisting of an imperforate envelope, exothermic material therein, one wall of said envelope being of imperforate paper formed of 30 pineapple husk fibres for transmitting moisture by capillary attraction and the other wall of said envelope being formed of metal foil of sufficient stiffness to hold the complete pad in position about a tress of hair to which it is applied. 35

FERDINAND RACEN.
